(57) **CLAIM**

We claim the ornamental design for a plastic bottle, as shown and described.

DESCRIPTION

FIG. 1 is a side elevation view of a plastic bottle showing the present invention, the opposite side being identical, the portions shown in phantom forming no portion of the ornamental design.

FIG. 2 is a plan view from the bottom of FIG. 1.

FIG. 3 is a plan view from the top of FIG. 1; and,

FIG. 4 is an elevated perspective view of the plastic bottle shown in FIG. 1.

The broken line showing is for illustrative purposes only, and forms no part of the claimed design.
